UNITED STATES PATENT OFFICE

JULIUS JUDELSOHN, OF NEW YORK, N. Y.

BOOTH CONSTRUCTION

Application filed February 21, 1929. Serial No. 341,708.

This invention relates to booth construction. It is particularly directed to a collapsible booth, such as a telephone booth comprised of separate, compact parts capable of 5 quick and easy assembly for permitting building up of the booth at the place of installation.

Among the objects of this invention is to provide a neat, rugged, durable, and substantially soundproof booth of the character described which shall be of economical construction, comprising few simple and compact parts readily adapted for storing and shipping, which shall be easy to assemble and dis- 10 assemble without the need of more than ordinary skill or use of bolts or other clamping devices, and which shall yet be practical and efficient to a high degree.

Other objects of this invention will in part 20 be obvious and in part hereinafter pointed out.

The invention accordingly consists in the features of construction, combinations of elements, and arrangement of parts which will 25 be exemplified in the construction hereinafter described, and of which the scope of application will be indicated in the following claims.

In the accompanying drawings, in which 30 is shown one of the various possible illustrative embodiments of this invention,

Fig. 1 is a perspective view of a telephone booth embodying the invention;

Fig. 2 is a cross-sectional view taken on 35 line 2—2 of Fig. 1;

Fig. 3 is a cross-sectional view taken on line 3—3 of Fig. 2;

Fig. 4 is an enlarged, perspective view of 40 a rear corner portion of the top cover of the booth;

Fig. 5 is an enlarged perspective view of the telephone rest supporting structure; and

Fig. 6 is an exploded perspective view of 45 the bottom, sides and top of the booth.

Referring in detail to the drawings, 10 designates a telephone booth embodying the invention. Said booth comprises generally a bottom or floor portion 11, a top or roof portion 12, side walls 13, 14, a rear wall 15,

a front door 16, and a telephone support and table 16a.

Said floor, roof, and wall portions comprise a number of separate partially built up, compact parts which may be easily assembled to 55 form a rigid structure in which the door and telephone support may be readily mounted.

The floor 11 and roof 12 as will hereinafter be described, in detail, are of rigid construction and are adapted to be interfitted and assembled with a pair of rear corner posts 18 and 19, front corner posts 20 and 21, side panels 25 and 26 and a rear panel 27.

Said floor portion 11 comprises a metal frame 16 extending around three sides of 60 the booth and supporting a panel 22. The bottom frame 16 comprises an integral substantially U-shaped member 30 having side and rear portions of angular cross-section, said member having an outer upstanding 65 flange 32 and an inwardly extending horizontal flange 33. Supported on said horizontal flange 33 is a U-shaped member 34 of angular cross-section comprising an outwardly extending horizontal flange 35, somewhat narrower than flange 33 and substantially abutting the inner surface 32a of vertical flange 32. Extending upwardly from said horizontal flange 35 is a vertical flange 37 parallel to 70 and spaced from flange 32 of member 30. A slot 38 is thus provided at the rear and side of frame 16 for frictionally receiving the lower edge portions 25a, 26a, and 27a of panels 25, 26 and 27 respectively. The angle members 30 and 35 are preferably rigidly secured to one another as by welding flange 35 to flange 33. Angularly shaped corner stays 75 78 may be fixed to the lower frame 16 at the four corners thereof, as by welding said stays to the upstanding flange 32 of said member 30. Said stay members 78 preferably project above said frame 16 and are adapted to contact adjacent lower end portions of said corner posts 18, 19, 20 and 21.

The panel 22 supported on frame 16 comprises a board 80 resting on the inner edge portions 33a of said horizontal flange 33, and is preferably made of soundproof material such as plaster board, cork board or the like. Superimposed over said board 80 is a metal 85 100

plate 81 secured thereto in any suitable manner. Said plate is preferably corrugated or ridged to add to the strength thereof, and also to provide a firm footing for persons using the booth. A molding 82 secured to upright flange 37 retains the panel 22 in fixed position. The front edge 80a of board 80 terminates flush with the inner surface of front stays 78, whereas the plate 81 extends 10 beyond said stays in a downwardly curved portion 81a. Said plate 81 is provided with cut-out portions 83, 84 for receiving the inwardly extending flanges 85 of said front stays 78.

15 Roof portion 12 comprises a frame 17, substantially similar to and symmetrically disposed with respect to frame 16, and extending about the sides and rear of the booth, a front frame 95, and a panel 23 supported by 20 said frames. Said frame 17 comprises a **U**-shaped member 40 of angular cross-section extending around the sides and rear of the booth, and being formed with an outer, downwardly extending vertical flange 41, and an 25 inwardly extending horizontal flange 42. A three sided angle member 43 is secured to member 40, as by welding the horizontal flange 44 of the former to horizontal flange 41 of the latter. Said angle member 43 is 30 further formed with a downwardly extending flange 45 spaced from flange 42 and forming therewith a slot 46 adapted to frictionally receive the upper edge portions 25b, 26b, 27b of panels 25, 26 and 27, respectively.

35 Said top frame 17 is provided with means for supporting the panel 23. To this end an angle member 85 is secured to flange 45 of angle member 43 as by welding the vertical flange 86 of said member 85 to said flange 45. Extending inwardly from said flange 86 is a horizontal flange 87 spaced from flange 41 of angle member 40. Panel 23 comprises a soundproof board 88 similar to board 80, and supported between spaced flanges 87 and 45 41. The groove 89 provided by said spaced flanges however, is somewhat larger than the thickness of board 88. Covering said board 88 is a substantially square sheet metal member 90 having a flange 90a seated on said board and extending between said board and flange 41. Said cover member 90 is provided with an upstanding wall portion 91 and a top portion 92 spaced from said board 88 to provide a shallow chamber 93 for housing wires, and the like purposes.

50 The front frame member 95 comprises an angular shaped member 96 having an inwardly extending horizontal flange 97 and a downwardly extending flange 98. Secured to 55 said flange 98 is an angular shaped member 99 having a vertical flange 100 preferably welded to flange 98 and extending beyond said flange as at 101. Extending inwardly from said flange 100 is a horizontal flange 60 102 parallel to and spaced from said hori-

zontal flange 97 a sufficient distance to form a groove 104 for receiving the front edge portion 88a of board 88 and the superimposed front side of flange 90a in a tight friction fit. Secured to the inner surface of the extension 70 101 is a channel-shaped bar 105 having side walls 106 preferably welded at their edges 107 to said extension. Secured to the outer side of said extension 101, as by welding, is a flat metal reinforcing strip 108. To the 75 outer surface of said strip 108, is secured a stamped sheet metal cornice member 109 having a vertical edge preferably welded to said strip. An ornamental downwardly and outwardly bent portion 110 extends from said cornice portion 109, preferably somewhat below extension 101. The side portions of frame 17 terminate short of edge portion 88a of said board 88, the ends of members 40, 43, 85 substantially abutting adjacent edge portions of member 95.

80 Secured to the four corners of frame 17 are angularly shaped corner stays 79 similar to stays 78 and symmetrically disposed thereto. Said stays 79 are preferably welded or otherwise secured to the outer surface of vertical flange 42, and project below said flange for contacting adjacent upper end portions of corner posts 18, 19, 20 and 21. Corner post 18 is provided with means for frictionally supporting adjacent side panels 25 and 27. To this end, said corner post comprises an elongated angle iron 48 having a rear flange 49 and side flange 50. Fixed to side flange 49 is an elongated angle iron 51 having a flange 52 welded or otherwise secured to flange 49, and a flange 53 spaced from said flange 50. Extending between flanges 50 and 53 and secured thereto, in any suitable manner, is an elongated angle iron 54 having a flange 55 welded to flange 50 and a flange 56 spaced from flange 49 and having edge contact with flange 53. The slot or groove 57 formed by spaced walls 53 and 55 frictionally receives side edge 25c of panel 25. Welded to the inner face of flange 53 is a flange 58 of an elongated angle member 59. Said angle member 59 is provided with a flange 60 spaced from flange 52 and forming therewith a groove or slot 61 for frictionally receiving edge portion 27c of panel 27.

105 Corner post 19 is similarly constructed and symmetrically disposed with respect to corner post 18, and is provided with a slot or groove 62 similar to groove 61 for receiving edge portion 27d of said panel 27. Said corner post 20 is further formed with a slot or groove 63 similar to slot 57 for frictionally receiving edge portion 26c of panel 26.

110 The front corner posts 20 and 21 are substantially similar and are symmetrically disposed. Each comprises an elongated angle member 65 having a side flange 66 and an inwardly extending front flange 67. Welded or otherwise secured to the inner surface of 115

front flange 67 is an outwardly extending flange 68 of an angle member 69, having a flange 70 parallel to and spaced from flange 66, and forming therewith a slot or groove 71. The groove 71 in corner post 20 is adapted to receive edge 25d of panel 25, while the corresponding groove 71 in corner post 21 is adapted to receive edge portion 26d of panel 26. As clearly shown in Fig. 2, flanges 67 extend inwardly beyond angle member 69 and 72. An elongated channel shaped member 73 is fixed within the corner formed by flange 70 and extension 72 of flange 67. Said channel 73 comprises wall 74 preferably welded to flange 70, a wall 75 spaced from and parallel to said wall 74, and a wall 76 interconnecting said walls 74, 75. Secured to wall 75 of the channel in corner post 20, is an elongated strip 76a welded to the inner portion of said wall, for a purpose hereinafter appearing.

It will be noted that the corner posts 18, 19 and 21 are all of equal lengths and that the panels 25, 26 and 27 are somewhat longer than said corner posts. In building up the booth 10, the corner posts are first assembled with panels 25, 26 and 27 by inserting the side edge portions of said panels in their respective grooves in the corner posts. The tight frictional fit is sufficient to clamp these parts together. The top and bottom edge portions of said panels, however, project above and below the ends of said corner posts. The floor and roof members 11 and 12 may then be fitted to the thus far assembled structure by inserting the lower and upper projecting edges of the panels 25, 26 and 27 in their respective grooves in frames 16 and 17. The ends of the corner posts are adapted to abut the adjacent edges of the frames 16 and 17 thus providing a rigid, compact structure.

Swingably mounted on wall 75 of channel 73 in corner post 21 as on hinges 115, is a door 116 comprising two sections 117, 118 having windows 117a, 118a. Said sections 117, 118 are hinged together as at 119, to permit section 117 to swing inwardly into the booth while section 118 swings against said section 117 into the position shown in dotted lines in Fig. 2. A handle 120 secured to section 118 is provided for moving the door from within the booth. For guiding the hinged door section 117, 118 to open and closed position, a channel shaped member 121 is secured to the undersurface of board 88 in a position inclined to the front of the booth.

Secured to section 118 adjacent the upper edge thereof is a bracket 122 on which is rotatably mounted a roller 123 projecting into the groove 124 of said channel 121. During opening and closing of the door 116, roller 123 is guided in said groove 124 by side walls 125 of said channel. In closed position, the outer edge portion 118b of section 118 contacts strip 76a of corner post 20.

The door 116, at the lower end thereof, preferably terminates short of the plate 81 and at its upper end short of channel member 105 to provide air ventilating spaces.

For supporting the telephone support and table 116a within the booth, adjacent corner post 19, a pair of similar Z-shaped brackets 130 are secured adjacent each other on the inner faces of flanges 58 and 60 of angle member 59 in corner post 19. Said brackets are secured at about the mid-portion of said angle member, and each is provided with upstanding hook portions 131. Spaced from said brackets 130 are two similar brackets 132, likewise secured to flanges 58, and 60 of said angle members, and similarly provided with upstanding hook portions 133. The supporting frame 134 shown in Fig. 5 for mounting a table 145 is provided with means for engaging said brackets 130, 132. Said frame 134 comprises a member 135 having arms 136, and 137 extending at right angles to one another, to permit the same to be fitted in a horizontal position in the corner formed by adjacent portions of the booth walls 14 and 15. Said arms are constructed of angular shaped metal and comprises a horizontal flange 138 and a vertical flange 139. Corner portions of said vertical flange are adapted to be engaged by hook portions 133 of upper brackets 132 for mounting said frame. An angle iron 140 having vertical flanges 141, is adapted to be engaged in hook portions 131 of lower brackets 130. A pair of connecting brace bars 143 are secured at their opposite ends to flanges 141 and flanges 139 respectively, thus forming a unitary frame which may be easily and quickly mounted or removed from brackets 130, 132. Secured to the horizontal flange 138 of frame 134 is a substantially triangular shaped platform or table 145 made of wood or any other suitable material, which serves as a telephone support or elbow rest, or other like purpose. Said table is grooved as at 146 to receive one end of a vertical board 147 which cuts the corner above the table to form a triangular chamber 147a. The upper edge portion 148 of said board may be received in a groove 149 formed in top board 88. The electric wiring and other telephone mechanism may be housed in chamber 147.

The entire booth is substantially sound proof, panels 25, 26, 27, 80 and 88 being made of sound proof material.

It will now be understood that the integral parts above described may be easily put together and assembled solely by friction clamping fits and that no bolts or screws are necessary. When the floor, roof and side walls have been assembled, the table and telephone support are simply hung in place on the bracket 130, 132 and the door secured in its place by hinging it to corner post 21. The floor, roof, corner posts, wall panels, door and

telephone support may be stored and shipped in knocked down condition, and the entire assembling operation may be done at the place of installation of the booth.

5. It will be further understood that where parts are above described as welded together, any other suitable rigid attachment means may be substituted.

It will thus be seen that there is provided a 10 device in which the several objects of this invention are achieved, and which is well adapted to meet the conditions of practical use.

As various possible embodiments might be made of the above invention, and as various 15 changes might be made in the embodiment set forth, it is to be understood that all matter herein set forth or shown in the accompanying drawings is to be interpreted as illustrative and not in a limiting sense.

20 Having thus described my invention I claim as new and desire to secure by Letters Patent:

1. In booth construction, a rectangular roof portion, a rectangular floor portion comprising a three-sided frame, side walls and a rear wall attached to said floor and roof portions a bottom panel supported in said frame and extending beyond the open side of said frame.

2. In booth construction, in combination, 30 a bottom member and a wall panel, said member having an upwardly extending grooved portion adapted to frictionally receive the bottom end edge portion of said panel, said bottom member having an inwardly extending flange, and a floor board mounted on said flange.

3. In booth construction, a floor portion for said booth comprising a three-sided member having an inwardly extending flange, a 40 sound proof board supported by said member having edge portions resting on said flange, a metal plate superimposed over said board and an elongated molding strip attached to said member adapted to retain said board and plate in position on said flange.

4. In booth construction, a floor portion for said booth comprising a three-sided member, a sound proof board supported by said member, and a metal plate superimposed over 50 said board, said plate having a downwardly curved portion extending beyond the open side of said frame.

5. In booth construction, a roof comprising a frame member having an inwardly extending groove, a sound proof board supported by said member and having an edge portion received in said groove, and a chamber forming member superimposed over and having a portion extending into said groove and a portion spaced from said board.

6. In booth construction, a rectangular roof comprising a three-sided frame, side walls and a rear wall attached to said frame, 65 a top panel supported by said frame, and a

member frictionally secured to the edge of said panel at the open side of said frame.

7. In booth construction, a roof comprising a three-sided frame, a panel supported by 70 said frame, and a member frictionally secured to the edge of said panel at the open side of said frame, said member being provided with an integrally formed, downwardly and outwardly extending cornice portion.

8. A corner post for booth construction 75 comprising an elongated member of angular cross-section having wall portions extending at an angle to each other, a second elongated member of angular cross-section having a wall fixed to the inner surface of one of said wall portions, and a second wall parallel to and spaced from the other of said wall portions and a third elongated member of angular cross-section having a wall fixed to the inner surface of the second wall of said 80 second member and a wall parallel to and spaced from the first wall of said second member.

9. A corner post for booth construction 85 comprising an elongated member of angular cross-section having wall portions extending at an angle to each other, a second elongated member of angular cross-section having a wall fixed to the inner surface of one of said wall portions, and a second wall parallel to and spaced from the other of said wall portions and a third elongated member of angular cross-section having a wall fixed to the inner surface of the second wall of said 90 second member, and a wall parallel to and spaced from the first wall of said second member, and a fourth elongated member of angular cross-section having a wall fixed to the inner surface of the said other wall portion of the first member, and a wall 95 spaced from and parallel to the first wall portion of said first named member and said second named wall of said fourth member having an edge substantially abutting the outer surface of the second wall of said second member.

10. In booth construction, a floor portion for said booth comprising a member of angular cross-section, having a bottom wall and an upstanding wall, a second member of angular cross-section having a bottom wall fixed to the first named bottom wall and projecting towards said upstanding wall and an upstanding wall parallel to said first named upstanding wall and forming a groove therewith, a board supported by said first named bottom wall, a metal plate superimposed over said board and a molding piece attached to said second named upstanding wall for retaining said metal plate and board in supported position.

11. In booth construction, a floor portion for said booth comprising a member of angular cross-section, having a bottom wall and an upstanding wall, a second member of 120

- angular cross-section having a bottom wall fixed to said first named bottom wall and projecting towards said upstanding wall, and an upstanding wall parallel to said first named upstanding wall and forming a groove therewith, a board supported by said first named bottom wall, a metal plate superimposed over said board and a molding piece attached to said second named upstanding wall for retaining said metal plate and board in seated position on said first named bottom wall, and an upstanding panel having a bottom edge portion frictionally received within said groove. 5 70
- 10 12. A corner post for a booth comprising an elongated member of angular cross-section, a second elongated member of angular cross-section having a wall portion fixed to the inner surface of one of the walls of the first named member, and a second wall parallel to the other of the walls of the first member, and a channel shaped member having a wall fixed to the second wall of said second member and abutting the inner surface of the first wall of said first member, said channel shaped member having a second wall parallel to the first wall thereof and a third wall interconnecting the first two walls thereof and parallel to the first wall of said first member. 20 25 30 35 40 45 50 55 60 65 70 75 80 85 90 95 100 105 110 115 120 125 130
13. A corner post for a booth comprising an elongated member of angular cross-section, a second elongated member of angular cross-section having a wall portion fixed to the inner surface of one of the walls of the first named member, and a second wall parallel to the other of the walls of the first member, and a channel shaped member having a wall fixed to the second wall of said second member and abutting the inner surface of the first wall of said first member, said channel shaped member having a second wall parallel to the first wall thereof, and a third wall interconnecting the first two walls thereof and parallel to the first wall of said first member, and an elongated strip attached to the outer surface of the second wall of said channel shaped member adjacent the third wall thereof. 135
14. A top wall for a booth comprising a member of angular cross-section having a horizontal wall and a downwardly extending wall, a second member of angular cross-section having a horizontal wall fixed to the inner surface of said first horizontal wall and projecting towards said downwardly extending wall, and a second wall parallel to said downwardly extending wall and forming a groove therewith, and a third member of angular cross-section having a wall fixed to said second wall of said second member and having a second wall parallel to and spaced from said first mentioned horizontal wall and forming a groove therewith. 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
15. A top wall for a booth comprising a member of angular cross-section having a horizontal wall and a downwardly extending wall, a second member of angular cross-section having a horizontal wall fixed to the inner surface of said first horizontal wall and projecting towards said downwardly extending wall, and a second wall parallel to said downwardly extending wall and forming a groove therewith, and a third member of angular cross-section having a wall fixed to said second wall of said second member and a second wall parallel to and spaced from said first mentioned horizontal wall and forming a groove therewith, a board having an edge portion frictionally received within said second mentioned groove and a cover member having a portion extending between said board and said first mentioned horizontal wall and an integral portion spaced above said board and forming a chamber therewith. 80 85 90 95 100 105 110 115 120 125 130
16. A top wall for a booth comprising a member of angular cross-section having a horizontal wall and a downwardly extending wall, a second member of angular cross-section having a horizontal wall fixed to the inner surface of said first horizontal wall, and a second wall parallel to said downwardly extending wall and forming a groove therewith and a third member of angular cross-section having a wall fixed to said second wall of said second member, and a second wall parallel to and spaced from said first mentioned horizontal wall and forming a groove therewith, a board having an edge portion frictionally received within said second mentioned groove, a cover member having a portion extending between said board and said first mentioned horizontal wall and an integral portion spaced above said board and forming a chamber therewith, and a vertical panel having an upper edge portion frictionally received within said first mentioned groove. 95 100 105 110 115 120 125 130
17. In booth construction, a floor portion for said booth comprising a member of angular cross-section having a bottom wall and an upstanding wall, a second member of angular cross-section having a bottom wall fixed to said first named bottom wall, and an upstanding wall parallel to said first named upstanding wall and forming a groove therewith, a board supported by said first named bottom wall, a metal plate superimposed over said board and a molding piece attached to said second named upstanding wall for retaining said metal plate and board in supported position. 110 115 120 125 130
18. In booth construction, a floor portion for said booth comprising a member of angular cross-section having a bottom wall and an upstanding wall, a second member of angular cross-section having a bottom wall fixed to said first named bottom wall, and an upstanding wall parallel to said first named upstanding wall and forming a groove there- 130

with, a board supported by said first named bottom wall, a metal plate superimposed over said board, a molding piece attached to said second named upstanding wall for retaining said metal plate and board in supported position, an upstanding panel having a bottom edge portion frictionally received within said groove, a post having a groove frictionally receiving the side edge portion of said panel, 10 abutting the top edges of said upstanding walls of said first and second members.

19. In booth construction, a floor portion for said booth comprising a member of angular cross-section having a bottom wall and an upstanding wall, a second member of angular cross-section having a bottom wall fixed to said first named bottom wall, and an upstanding wall parallel to said first named upstanding wall and forming a groove therewith, a board supported by said first named bottom wall, a metal plate superimposed over said board, a molding piece attached to said second named upstanding wall for retaining said metal plate and board in supported position, an upstanding panel having a bottom edge portion frictionally received within said groove, a post having a groove frictionally receiving the side edge portion of said panel, 20 abutting the top edges of said upstanding walls of said first and second members, and a member fixed to the outer surface of the upstanding wall of said first member, having an upwardly extending portion adapted to contact the outer surface of said post adjacent 25 the lower end thereof.

20. A top wall for a booth comprising a member of angular cross-section having a horizontal wall and a downwardly extending wall, a second member of angular cross-section having a horizontal wall fixed to the inner surface of said first horizontal wall and projecting towards said downwardly extending wall, and a second wall parallel to said downwardly extending wall and forming a 45 groove therewith, and a third member of angular cross-section having a wall fixed to said second wall of said second member and having a second wall parallel to and spaced from said first mentioned horizontal wall 50 and forming a groove therewith, and sound proof members having edge portions frictionally received in said grooves.

21. In booth construction, in combination, a corner post comprising an elongated member of angular cross-section having wall portions extending at an angle to each other, a second elongated member of angular cross-section having a wall fixed to the inner surface of one of said wall portions, and a second 55 wall parallel to and spaced from the other of said wall portions, and forming a groove therewith and a third elongated member of angular cross-section having a wall fixed to the inner surface of the second wall of said second member, and a wall parallel to and

spaced from the first wall of said second member and forming a groove therewith, and a pair of panels, each having a side edge portion received in one of said grooves.

22. In booth construction, in combination, 70 a corner post comprising an elongated member of angular cross-section having wall portions extending at an angle to each other, a second elongated member of angular cross-section having a wall fixed to the inner surface of one of said wall portions and a second wall parallel to and spaced from the other of said wall portions, and a third elongated member of angular cross-section having a wall fixed to the inner surface of 75 the second wall of said second member, and a wall parallel to and spaced from the first wall of said second member and forming a groove therewith, and a flat panel having an edge portion received within said groove. 80

23. In booth construction, in combination, 85 a corner post comprising an elongated member of angular cross-section having wall portions extending at an angle to each other, a second elongated member of angular cross-section having a wall fixed to the inner surface of one of said wall portions, and a second wall parallel to and spaced from the other of said wall portions, and a third elongated member of angular cross-section having a wall fixed to the inner surface of said second wall of said second member, and a wall parallel to and spaced from the first wall of said second member and forming a groove therewith, and fourth elongated member of angular cross-section having a wall fixed to the inner surface of said second wall of said second member, said fourth member having a second wall spaced from and parallel to said first wall portion of said first named member and having an edge substantially abutting the outer surface of said second wall of said second member, and a pair of sound 90 proof panels, forming walls for said booth, having side edge portions frictionally received within said grooves. 100

24. In booth construction, in combination, 105 a floor for said booth comprising a three sided member formed of a pair of members of angular cross-section attached to each other and forming an upwardly extending groove and an inwardly extending ledge, a board having an edge portion supported on said ledge and a panel having a bottom edge portion frictionally received within said groove. 110

25. In booth construction, in combination, 115 a floor for said booth comprising a three sided member formed of a pair of members of angular cross-section attached to each other and forming an upwardly extending groove and an inwardly extending ledge, a board having an edge portion supported on 120

125

5 said ledge and a panel having a bottom edge portion frictionally received within said groove, and a corner post comprising a plurality of members of angular cross-section attached together and forming a groove receiving a side edge portion of said panel.

10 26. In booth construction, a floor portion comprising an elongated member of angular cross-section, having a bottom wall and an upstanding wall, a second member of angular cross-section having a bottom wall fixed to said first named bottom wall and an upstanding wall parallel to said first named upstanding wall and forming a groove there-
15 with, an upstanding panel having a bottom edge received in said groove and a bottom board supported on one of said bottom walls.

20 27. In booth construction, a floor portion comprising an elongated member of rectangular cross-section having a bottom wall and an upstanding wall, a second elongated member fixed to said first named bottom wall and having an upstanding wall parallel to said first named upstanding wall and forming a
25 groove therewith, a bottom board having an edge portion frictionally received within and an upstanding panel having a bottom edge portion frictionally received within said groove.

30 28. In booth construction, a floor portion for said booth comprising an elongated member of angular cross-section having a bottom wall and an upstanding wall, a second elongated member fixed to said first named bottom wall and having an upstanding wall parallel to said first named upstanding wall and forming a groove therewith, a bottom board having an edge portion supported by said bottom wall, an upstanding panel
35 having a bottom edge portion frictionally received within said groove, and an upstanding post having a groove frictionally receiving a side edge portion on said panel and abutting the top edges of said upstanding walls.

40 45 In testimony whereof I affix my signature.
JULIUS JUDELSON.
